190,274

SHOWER FAUCET AND TEMPERATURE DIAL COMBINATION

Howard E. Peterson, Modesto, Calif. (1100 Freemont, South Pasadena, Calif.), and Everett W. Peterson, 6443 Hazel Ave., Richmond, Calif.

Filed Aug. 12, 1958, Ser. No. 52,180

Term of patent 14 years

(Cl. D91—3)

Fig. 1.

Fig. 2.

Figure 1 is a front perspective view of a shower faucet and temperature dial combination showing our new design;

Figure 2 is a side view thereof.

The dominant portions of the design are indicated in the solid lines.

We claim:

The ornamental design for a shower faucet and temperature dial combination, substantially as shown and described.
